(57) **CLAIM**

The ornamental design for a vehicle bumper, as shown and described.

DESCRIPTION

FIG. 1 is a top, front, left isometric view of an ornamental design for a vehicle bumper;

FIG. 2 is a top, front, right isometric view of the vehicle bumper of FIG. 1;

FIG. 3 is a front elevation view of the vehicle bumper of FIG. 1; and,

FIG. 4 is a top view of the vehicle bumper of FIG. 1.

The ornamental design that is claimed is shown in solid lines in the drawings. The broken lines in the drawings illustrate portions of a vehicle bumper that form no part of the claimed design. The dash-dash-dash broken lines in the drawings are included for the purpose of illustrating portions of the vehicle bumper that form no part of the claimed design. The dash-dot-dash broken lines in the drawings are included to define unclaimed boundaries of the claimed design and form no part of the claimed design.
